UNITED STATES PATENT OFFICE

2,489,811

BELT POLISHING AND GRINDING MACHINE

Henry G. Perkins, Kalamazoo, Mich., assignor to Hammond Machinery Builders, Kalamazoo, Mich.

Application March 31, 1948, Serial No. 18,152

12 Claims. (Cl. 51—145)

1

This invention relates to improvements in belt polishing and grinding machine.

The principal objects of this invention are:

First, to provide a belt polishing or grinding machine for use with a turret type rotatable work holder in which the belt and its driving mechanism can be universally adjusted to operate upon various portions of work pieces carried by the chucks on the turret.

Second, to provide an angularly adjustable belt grinder with a backing roll for yieldably supporting the working reach of the belt.

Third, to provide an angularly adjustable belt grinder for use in combination with a multi-head automatic turret type work holder in which the grinding belt and its drive mechanism is automatically tilttable away from the work holder to permit rotation and indexing of the turret.

Fourth, to provide novel means for supporting and angularly and laterally adjusting a belt type grinder and its driving mechanism.

Other objects relating to details of the invention will appear from the description to follow. The invention is defined in the claims.

The drawings of which there are two sheets illustrate a preferred form of my grinder and polisher.

Fig. 1 is an elevational view of my grinder and for purpose of description may be referred to as a side elevational view.

Fig. 2 is a fragmentary plan view of the belt portion of my grinder with the motor broken away.

Fig. 3 is a fragmentary front elevational view of the belt portion of my grinder and the adjustable portion of its support.

Fig. 4 is a fragmentary vertical cross sectional view taken along the plane of the line 4—4 in Fig. 3.

Fig. 5 is a plan view illustrating conventionally one possible arrangement of four of my belt grinders relative to a turret type work holder.

My machine which will be referred to for convenience as a grinder is particularly designed to be used in combination with multi-head rotary turret type work holders having a plurality of work holding spindles or chucks thereon. The work holder is of a well known automatically operated type and its details form no part of this invention. The turret type work holder is conventionally illustrated at 1 in Fig. 5 and is provided with six work holding spindles or chucks 2 which are individually rotatable on their axes and bodily rotatable with the turret between four working stations 3, an unloading station 4 and 50

2

a loading station 5. Four of my belt grinders are illustrated conventionally at 6 in various operating positions relative to the working stations 3.

My grinder is provided with a base 7 having the generally horizontal beveled slide portions 8 formed on one side thereof. The slide portions are engageable with and support the beveled ways 9 formed on one side of a pedestal 10. The pedestal is adjustable laterally on the slides 8 by operation of the screw member 11 in a manner which will be readily understood by persons skilled in the art.

The pedestal 10 carries a vertical column 12 which is vertically adjustable on the pedestal by operation of the hand wheel 13. The upper end of the column 12 is shaped to provide the spaced ears 14 forming a yoke. Just below the yoke 14 the column 12 is provided with a flat face 15 to which is bolted a hydraulic or pneumatic cylinder 16. The cylinder 16 is provided with a piston, the piston rod of which projects upwardly from the cylinder as at 17 in Fig. 3.

A head member 18 is pivotally supported between the ears 14 by the pin 19 and extends laterally over the cylinder 16 where it is provided with a boss 20 engageable with the end of the piston rod 17. The cylinder 16 is arranged to be supplied with a fluid under pressure by means of the hose 21 (see Fig. 1) and it is contemplated that the fluid pressure will be controlled by mechanism (not illustrated) in timed relationship with a cycle or operation of the turret 1 so that the head 18 will be tilted by an extension of the piston rod 17 during transfer and indexing movement of the work holders 2.

The head 18 has a semi-cylindrical upper portion 22 defining a transverse aperture in which is journaled the tilt shaft 23. The forward end of the tilt shaft carries a pinion 24 and the front face of the head is provided with forwardly projecting arms 25 rotatably supporting the worm 26. The worm 26 is operatively engaged with the pinion 24 and is provided with a square or noncircular end 27 by means of which the worm may be turned to rotate the pinion and shaft. The rear end of the tilt shaft 23 is non-rotatably connected to a tilt bar 28 whereby the tilt bar is rotatable in a vertical plane through 360°.

In order to limit the rotation of the tilt bar and clamp it against accidental rotation the head 22 is provided with laterally projecting flanges 29 defining arcuate slots 30 and a holding plate 31 is non-rotatably clamped to the tilt bar 28 and positioned between the flanges 29 and the

forward face of the tilt bar. The tilt bar and holding plate define a series of tapped apertures 32 angularly arranged about the shaft 23 and arranged to receive clamping screws 33 extending through the slots 30.

The rear face of the tilt bar 28 defines the tapered ways 34 which slidably engage mating portions on a slide bar 35. The slide bar carries a screw 36 engaged with an ear 37 on the tilt bar 28 to adjust the slide bar laterally. The slide bar 35 defines a slot 38 receiving the support arm 39 which is pivotally secured in the slot by the pivot bolt 40. The slide bar is provided with an arcuate slot 41 (see Fig. 2) through which the clamping screw 42 extends to engage the support arm and clamp the arm to the slide bar.

The left or inner end of the arm 39 (as viewed in Fig. 3) is provided with a flange 43 bolted to one side of the platelike support member 44. The rear corner of the plate 44 carries the bushing 45 which rotatably supports the drive shaft 46. The left or inner end of the shaft 46 carries a drive pulley 47 and the outer end of the shaft carries the multi-V-belt pulley 48. The upper edge of the plate 44 carries the laterally disposed and sloping mounting plate 49 on which an electric motor 50 is supported. The motor is arranged to drive the drive shaft with the V-belts 51.

The forward edge of the plate 44 is provided with a boss 52 supporting the idler shaft 53. The idler shaft 53 serves to rotatably support an idler pulley 54 in the plane of the drive pulley 47. The idler shaft 53 also pivotally supports the forward end of an arm 55. The arm 55 extends rearwardly between the pulleys 47 and 54 and the plate 44 and immediate of its ends is enlarged as at 56 to receive the stub shaft 57. The lower edge of the plate 44 is notched or cut away as at 58 to clear the enlarged portion of the arm. The stub shaft 57 rotatably carries a backing wheel 59.

The rear end of the arm 55 is urged downwardly by a coil spring 60, the upper end of which bears against an adjusting screw 61 threaded through a boss 62 secured to the side of the plate 44. The lock nut 63 is provided for clamping the screw in its adjusted position.

Located generally above the backing wheel 59 and secured to the side of the plate 44 as by welding is a yoke shaped bracket 64 the arms of which are apertured to pass the threaded rod 65. A coil spring 66 is positioned between one arm of the bracket 64 and a nut 67 threaded on the rod to urge the rod upwardly and forwardly in the bracket. The upper end of the rod 65 carries a yoke 68 rotatably supporting a tracking pulley 69.

A continuous abrasive belt 70 is looped around the pulleys 47, 54, and 69 and the nut 67 can be adjusted to vary the tension in the belt. Suitable adjusting means not illustrated but well known in the art can be employed to turn the rod 65 in the bracket 64 to tilt the pulley 69 and cause the belt to track accurately on the pulley. Adjustment of the screw 61 will vary the pressure with which the backing wheel 59 is pressed against the inside of the belt 70 between the drive pulley 47 and idler pulley 54.

From the foregoing discussion it should be apparent that a grinder can be located adjacent to one of the working stations 3 of the turret 1 and vertically and laterally adjusted by means of the screw 11 and the hand wheel 13. The tilt bar and support arm can then be tilted by operation of the worm and pinion 24 and 26 to bring the working reach of the belt 70 into the general surface which it is desired to grind on the work 75 and idler pulleys, and a spring adjustably com-

piece. Angular adjustment of the belt and grinder in a second plane can then be effected by swinging the arm 39 in the slot 38 and the grinder can be clamped in a position by tightening the screws 42 and 33. With the fluid hose 21 connected through the automatic controls of the turret my grinder can be made to tilt away from each succeeding work piece while the piece is indexed and then swing back into operating position to rapidly grind or polish any given surface on the work piece.

The pressure of the spring 60 can be completely relaxed in which case the working reach of the belt can be made to wrap around and conform to a surface of the work which is curved longitudinally with respect to the axis of the work. The belt will thus grind surfaces which it would be impossible to grind with a grinding wheel.

The combination of the turret type work holder 20 and several of my grinders is particularly effective to completely finish a work piece at one manual operation because by proper adjustment of the screws 61 on the several grinders, the belts can be arranged to operate on all surfaces of the 25 work piece. Part of the backing wheels 59 can be adjusted to have tight contact with the work to 30 grind a regular surface of rotation while others of the backing wheels may be backed off to permit the belt to wrap around and conform to 35 curved surfaces as described above.

I have thus described a highly practical commercial embodiment of my belt grinder so that others may reproduce the same with such minor modifications as desired without further description.

Having thus described my invention, what I claim as new and desire to secure by Letters Patent is:

1. A belt grinding and polishing machine 40 adapted to be used in conjunction with and adjusted relative to the turret of a rotary work holder comprising, a base having a vertical column adjustably carried thereby for vertical and lateral adjustment relative to said base, a yoke on the top of said column, a fluid operated cylinder carried by the upper end of said column and having an upwardly extending piston rod, a head pivotally mounted on said yoke and overlying said piston rod for periodic tilting engagement thereby, a generally horizontal tilt shaft journaled in said head and having a pinion, a worm carried by said head for turning said pinion, a tilt bar secured to said shaft and having a set of ways formed therein, a slide bar mounted in 45 said ways, screw means for adjusting said slide bar on said tilt bar, a support arm on said slide bar arranged for tilting adjustment about an axis normal to said shaft, a platelike support member secured to the end of said support arm and having a flange on its upper edge, a motor mounted on said flange, a driving pulley rotatably mounted on said support member and arranged to be driven by said motor, an idler pulley rotatably mounted on said support member, a yoke member 50 rotatably mounted and linearly adjustably mounted on said support member, spring means urging said yoke member away from said pulleys, a third pulley supported by said yoke member, an abrasive belt rotatably mounted on said 55 pulleys, a lever arm journaled on the same shaft as said idler pulley, an idle shaft carried by said lever arm, said support member being cut away to clear said idle shaft, a backing wheel mounted on said idle shaft and located between said driving 60 and idler pulleys, and a spring adjustably mounted on said support member, spring means urging said yoke member away from said pulleys, a third pulley supported by said yoke member, an abrasive belt rotatably mounted on said 65 pulleys, a lever arm journaled on the same shaft as said idler pulley, an idle shaft carried by said lever arm, said support member being cut away to clear said idle shaft, a backing wheel mounted on said idle shaft and located between said driving and idler pulleys, and a spring adjustably com-

pressed between said support member and said lever arm for urging said backing wheel against the inside of said belt.

2. A belt grinding and polishing machine comprising, a base having a column adjustably carried thereby for vertical and lateral adjustment relative to said base, a yoke on the top of said column, a fluid operated cylinder carried by the upper end of said column and having an upwardly extending piston rod, a head pivotally mounted on said yoke and overlying said piston rod for periodic tilting engagement thereby, a generally horizontal tilt shaft journaled in said head and having a pinion, a worm carried by said head for turning said pinion, a tilt bar secured to said shaft and having a set of ways formed therein, clamping screws for clamping said tilt bar to said head, a slide bar mounted in said ways, screw means for adjusting said slide bar on said tilt bar, a support arm on said slide bar arranged for tilting adjustment about an axis normal to said shaft, a platelike support member having a flange on its upper edge and secured to the end of said support arm, a motor mounted on said flange, a driving pulley rotatably mounted on said support member and arranged to be driven by said motor, an idler pulley rotatably mounted on said support member, a yoke member rotatably and linearly adjustably mounted on said support member, spring means urging said yoke member away from said pulleys, a third pulley supported by said yoke member, an abrasive belt rotatably mounted on said pulleys, a lever arm journaled on the same shaft as said idler pulley, an idle shaft carried by said lever arm, a backing wheel mounted on said idle shaft and located between said driving and idler pulleys, and spring means adjustably compressed between said support member and said lever arm for urging said backing wheel against the inside of said belt.

3. A belt grinding and polishing machine comprising, a column, a yoke on the top of said column, a fluid operated cylinder carried by the upper end of said column and having an upwardly extending piston rod, a head pivotally mounted on said yoke and overlying said piston rod for periodic tilting engagement thereby, a generally horizontal tilt shaft journaled in said head and having a pinion, a worm carried by said head for turning said pinion, a tilt bar secured to said shaft and having a set of ways formed therein, a slide bar mounted in said ways, screw means for adjusting said slide bar on said tilt bar, a support arm on said slide bar arranged for tilting adjustment about an axis normal to said shaft, a platelike support member secured to the end of said support arm, a motor mounted on said support member, a driving pulley rotatably mounted on said support member and arranged to be driven by said motor, an idler pulley rotatably mounted on said support member, a yoke member linearly adjustably mounted on said support member, spring means urging said yoke member away from said pulleys, a third pulley supported by said yoke member, an abrasive belt rotatably mounted on said pulleys, a lever arm tiltably mounted on said support member for motion parallel to said support member, an idle shaft carried by said lever arm, a backing wheel mounted on said idle shaft and located between said driving and idler pulleys, and spring means adjustably compressed between said support member and said lever arm for urging said backing wheel against the inside of said belt.

4. A belt grinding and polishing machine comprising, a column, a yoke on the top of said column, a fluid operated cylinder carried by the upper end of said column and having an upwardly extending piston rod, a head pivotally mounted on said yoke and overlying said piston rod for periodic tilting engagement thereby, a generally horizontal tilt shaft journaled in said head, screw means carried by said head for turning said tilt shaft, a tilt bar secured to said shaft, a support arm on said tilt bar arranged for tilting adjustment about an axis normal to said shaft, a platelike support member secured to the end of said support arm, a motor mounted on said support member, a driving pulley rotatably mounted on said support member and arranged to be driven by said motor, an idler pulley rotatably mounted on said support member, a third pulley supported by said support member, an abrasive belt rotatably mounted on said pulleys, a lever arm tiltably mounted on said support member, an idle shaft carried by said lever arm, a backing wheel mounted on said idle shaft and located between said driving and idler pulleys, and spring means adjustably compressed between said support member and said lever arm for urging said backing wheel against the inside of said belt.

5. A belt grinding and polishing machine adapted to be used in conjunction with and adjusted relative to the turret of a rotary work holder comprising a base, a support arm on said base arranged for tilting adjustment longitudinally of the arm about a horizontal axis and laterally of the arm about a movable axis extending transversely through the arm, a platelike support member secured transversely across the end of said support arm and having a flange on its upper edge, a motor mounted on said flange, a driving pulley rotatably mounted on said support member and arranged to be driven by said motor, an idler pulley rotatably mounted on said support member, a yoke member rotatably and linearly adjustably mounted on said support member, spring means urging said yoke member away from said pulleys, a third pulley supported by said yoke member, an abrasive belt rotatably mounted on said pulleys to rotate in a plane parallel to said second axis, a lever arm journaled on the same shaft as said idler pulley, an idle shaft carried by said lever arm, said support member being cut away to clear said shaft, a backing wheel mounted on said idle shaft and located between said driving and idler pulleys, and spring means adjustably compressed between said support member and said lever arm for urging said backing wheel against the inside of said belt.

6. A belt grinding and polishing machine adapted to be used in conjunction with and adjusted relative to the turret of a rotary work holder comprising, a base, a support arm on said base arranged for tilting adjustment, longitudinally of the arm about a horizontal axis and laterally of the arm about a movable axis extending transversely through the arm, a platelike support member secured transversely across the end of said support arm and having a flange on its upper edge, a motor mounted on said flange, a driving pulley rotatably mounted on said support member and arranged to be driven by said motor, an idler pulley rotatably mounted on said support member, a yoke member rotatably and linearly adjustably mounted on said support member, spring means urging said yoke member

away from said pulleys, a third pulley supported by said yoke member, an abrasive belt rotatably mounted on said pulleys to rotate in a plane parallel to said second axis, a lever arm pivoted on said support member, an idle shaft carried by said lever arm, a backing wheel mounted on said idle shaft and located between said driving and idler pulleys, and spring means adjustably compressed between said support member and said lever arm for urging said backing wheel against the inside of said belt.

7. A belt grinding and polishing machine comprising, a base, a support arm on said base arranged for tilting adjustment longitudinally of the arm about a generally horizontal axis and laterally of the arm about a movable axis transverse to the arm, a support member secured to the end of said support arm, a motor mounted for tilting motion longitudinally with said support arm, a driving pulley rotatably mounted on said support member and arranged to be driven by said motor, an idler pulley rotatably mounted on said support member, a yoke member linearly adjustably mounted on said support member, means urging said yoke member away from a line between said pulleys, a third pulley supported by said yoke member, an abrasive belt rotatably mounted on said pulleys to rotate in a plane parallel to said second axis, a lever arm pivoted on said support member, an idle shaft carried by said lever arm, a backing wheel mounted on said idle shaft and located between said driving and idler pulleys, and spring means carried by said support member for urging said backing wheel against the inside of said belt.

8. A belt grinding and polishing machine comprising, a base, a support arm on said base arranged for tilting adjustment longitudinally of the arm about a generally horizontal axis and laterally of the arm about a movable axis transverse to the arm, a support member secured to the end of said support arm, a motor mounted for tilting motion longitudinally with said support arm, a driving pulley rotatably mounted on said support member and arranged to be driven by said motor, an idler pulley rotatably mounted on said support member, a third pulley linearly adjustably mounted on said support member, means urging said third pulley away from a line between said other pulleys, an abrasive belt rotatably mounted on said pulleys to rotate in a plane parallel to said second axis, a lever arm pivoted on said support member, an idle shaft carried by said lever arm, a backing wheel mounted on said idle shaft and located between said driving and idler pulleys, and spring means carried by said backing member for urging said support wheel against the inside of said belt.

9. A belt grinding and polishing machine comprising, a column, a fluid operated cylinder carried by the upper end of said column and having an upwardly extending movable portion, a head pivotally mounted on said column and overlying said movable portion for tilting engagement thereby, a generally horizontal tilt shaft journaled in said head, screw means carried by said head for turning said tilt shaft, a tilt bar secured to said shaft, a support arm on said tilt bar arranged for tilting adjustment about an axis normal to said shaft, a platelike support member secured to the end of said support arm, a motor mounted on said support member, a driving pulley rotatably mounted on said support member and arranged to be driven by said motor, an idler pulley rotatably mounted on said support

member, a third pulley supported by said support member, an abrasive belt rotatably mounted on said pulleys, a lever arm tiltably mounted on said support member, an idle shaft carried by said lever arm, a backing wheel mounted on said idle shaft and located between said driving and idler pulleys, and spring means adjustably compressed between said backing member and said lever arm for urging said support wheel against the inside of said belt.

10. In combination with a turret type rotary work holder having a plurality of spindles rotatable about their individual axes and translatable between a plurality of working stations,

15 a plurality of grinding mechanisms associated with said working stations, each of said mechanisms comprising, a base, an extensible support arm projecting from said base and arranged for tilting adjustment longitudinally of the arm

20 about a generally horizontal axis and laterally of the arm about a movable axis transverse to the arm, a support member secured to the end of said support arm, a motor mounted for tilting motion longitudinally with said support arm, a

25 driving pulley rotatably mounted on said support member and arranged to be driven by said motor, an idler pulley rotatably mounted on said support member, a yoke member linearly adjustably mounted on said support member, means urging

30 said yoke member away from a line between said pulleys, a third pulley supported by said yoke member, an abrasive belt rotatably mounted on said pulleys, a lever arm pivoted on said support member, an idle shaft carried by said lever arm,

35 a backing wheel mounted on said idle shaft and located between said driving and idler pulleys, and spring means carried by said support member for urging said backing wheel against the inside of said belt.

40 11. In combination with a turret type rotary work holder having a plurality of spindles rotatable about their individual axes and translatable between a plurality of working stations, a plurality of grinding mechanisms associated with

45 said working stations, each of said mechanisms comprising, a column, a fluid operated cylinder carried by the upper end of said column and having an upwardly extending movable portion, a head pivotally mounted on said column and overlying said movable portion for tilting engagement

50 thereby, a generally horizontal tilt shaft journaled in said head, screw means carried by said head for turning said tilt shaft, a tilt bar secured to said shaft, a support arm on said tilt bar arranged for

55 tilting adjustment about an axis normal to said shaft, a platelike support member secured to the end of said support arm, a motor mounted on said support member, a driving pulley rotatably mounted on said support member and arranged

60 to be driven by said motor, an idler pulley rotatably mounted on said support member, a third pulley supported by said support member, an abrasive belt rotatably mounted on said pulleys, a lever arm tiltably mounted on said support

65 member, an idle shaft carried by said lever arm, a backing wheel mounted on said idle shaft and located between said driving and idler pulleys, and spring means adjustably compressed between said backing member and said lever arm for urging said support wheel against the inside of said belt.

70 12. In combination with a turret type rotary work holder having a plurality of spindles rotatable about their individual axes and translatable between a plurality of working stations, a plu-

rality of grinding mechanisms associated with said working stations, each of said mechanisms comprising, a base, a support arm extensible from and vertically adjustable on said base and arranged for tilting adjustment longitudinally of the arm about a generally horizontal axis and laterally of the arm about a movable axis transverse to the arm, a support member secured to the end of said support arm, a motor mounted on said support member, a driving pulley rotatably mounted on said support member and arranged to be driven by said motor, an idler pulley rotatably mounted on said support member, a third pulley linearly adjustably mounted on said support member, means urging said third pulley away from said other pulleys, and an abrasive belt rotatably mounted on said pulleys.
